UNITED STATES PATENT OFFICE.

CARL F. STOLTZ, OF DELHI, OHIO, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 2, 1928. Serial No. 251,259.

My invention relates to railway traffic controlling apparatus, and particularly to apparatus of the type intended for safely controlling railway traffic governing devices, such as switches and signals, from a point remote from such devices.

I will describe one form of railway traffic controlling apparatus embodying my invention, and will then point out the novel features thereof in claims.

In the accompanying drawings, Figs. 1 and 2 when placed end to end with Fig. 1 on the left, form a diagrammatic view showing one form of railway traffic controlling apparatus embodying my invention.

Referring to the drawing, the reference characters 1 and 1^a designate the track rails of a stretch of railway track connected with a siding 4 by a switch 3 of the usual and well known form. The rails 1 and 1^a of the main track are divided, by means of insulated joints 2, to form a plurality of successive track sections A—B, B—C, C—D, D—E, E—F and F—G. The rails of the siding 4 are similarly divided to form a track section H—J, the rails of the siding to the left of point H being connected with the rails of section D—E in the usual manner. Each track section is provided with a track battery 5 connected across the rails adjacent one end of the section, and with a track relay connected across the rails adjacent the other end of the section and designated by the reference character R, with a suitable distinguishing exponent. Each track relay R, therefore, is normally energized, but is arranged to become de-energized when a train enters the corresponding section.

The reference character N designates a repeater relay which is energized when relay R⁴ is closed. The circuit for relay N may be traced from a suitable source of energy such as a battery 6 over wires 9, 10, 11, 12 and 14, front contact 15 of relay R⁴, wire 16, winding of relay N, wire 17, and common wire 18 back to battery 6.

An approach relay Y is normally energized by current which flows from battery 19 over wire 20, front contact 21 of relay R¹, wire 22, front contact 23 of relay R², wire 24, front contact 25 of relay R³, wire 26, winding of relay Y, and wire 27 back to battery 19. It follows that when an east-

bound train, that is, a train moving from left to right, passes point A, relay Y becomes de-energized and this relay remains de-energized until the train has passed point D. The approach relay Y controls a slow acting repeater relay P, the circuit for the latter relay passing from battery 6, through wires 9, 10, 11, 12, 28, 29 and 13, front contact 30 of relay Y, wire 31, winding of relay P and common wire 18 back to battery 6. It is apparent therefore that when relay Y is energized, relay P is also energized, but that when relay Y opens, as by the entrance of a train into section A—B, the circuit for relay P is interrupted as soon as relay Y opens its front contact. Due to the slow acting characteristics of relay P, a brief interval of time elapses after the de-energization of relay Y and prior to the opening of the front contacts of relay P. The functions of relays Y and P will be explained in detail hereinafter.

Westbound traffic from siding 4 into the main track over the switch 3 is governed by a signal S⁴ and westbound traffic through section D—E is governed by a signal S⁶. Eastbound traffic over the switch 3 is governed by two signals S³ and S⁵, which in the form here shown are mounted upon a single mast. The circuits for controlling signals S³, S⁵, S⁴ and S⁶ will be described hereinafter.

Located adjacent point B are two automatic signals S⁸ and S¹ for governing westbound and eastbound traffic, respectively. The signals S⁸ and S¹ may be controlled in any suitable manner and since the control of these signals forms no part of my present invention, the circuits are omitted from the drawing for the sake of simplicity. For present purposes it is sufficient to state that signal S⁸ is so controlled that the signal normally indicates proceed but is arranged to indicate stop when a westbound train occupies section A—B and to indicate caution if section A—B is unoccupied and the first section to the left of point A is occupied by a westbound train. Signal S⁸ is also placed at stop by an eastbound train when such train passes the first head block signal to the left of point B, and signal S⁸ remains at stop until the train has reached some point to the right of the signal.

Two signals S⁹ and S⁷ are located at point F for controlling eastbound traffic through

section F—G. These signals may be manually controlled but the controlling circuits have been omitted from the drawing because they form no part of my present invention.

Westbound traffic approaching the switch 3 is governed by a signal S^2 located at point G. This signal is controlled in part by a manually operable switch r and in part by a relay K^2 as will appear more in detail as the description proceeds.

Located adjacent switch 3 is a relay Q which is provided with a circuit from battery 6, through wires 9, 10, 11, 12, 28, 29, 32, 33, and 34, contact 35 controlled by signal S^4 , wire 36, contact 37 controlled by signal S^6 , wire 38, contact 39 controlled by signal S^5 , wire 40, contact 41 controlled by signal S^3 , wire 42, winding of relay Q, and common wire 18 back to battery 6. It will be observed that the circuit for relay Q contains contacts controlled by each of the signals governing traffic over the switch 3 and that each of these signals must be at stop in order to energize the relay Q. It will be manifest therefore, that when all of the signals associated with switch 3 are at stop, relay Q will be energized but that this relay will open if any one or more of the signals indicates caution or proceed.

Signal S^5 is controlled in part by a line relay K^5 , which is controlled in turn by traffic conditions in advance of the signal. One circuit for relay K^5 passes from battery 43, (Fig. 2) through wires 123, 44, 162 and 45, contact 46 controlled by signal S^2 , wire 47, pole changer a^9 controlled by signal S^9 , wire 48, front contact 49 of track relay R^6 , wire 50, front contact 51 of relay N, wire 52, winding of relay K^5 , wire 53, pole changer a^9 , and wires 64, 54, 55 and 96, back to battery 43. The circuit just traced is closed only when signals S^2 and S^9 indicate stop and when relays R^6 and N are both energized. Under which conditions current supplied to relay K^5 energizes this relay in what I shall term the reverse direction so that its polar contact is swung to the left. If, however, signal S^9 indicates caution or proceed, the pole changer a^9 is reversed, the other parts of the circuit just traced remaining closed, and the polarity of the current supplied to relay K^5 is then reversed. With signal S^9 indicating caution or proceed, therefore, relay K^5 is energized in the normal direction so that its polar contact is swung to the right.

Relays K^4 and K^6 are connected in parallel and are at times supplied with energy through a pole changer a^8 controlled by signal S^8 . Relay K^4 is a neutral relay and is energized by current of either polarity, but relay K^6 has a polar armature, which is responsive to the polarity of the current supplied to the relay. As shown in the draw-

ing, signal S^8 indicates proceed and under these conditions, current from battery 56 flows through pole changer a^8 , wire 57, front contact 58 of relay R^2 , wire 59, front contact 60 of relay R^3 , wire 61, front contact 62 of track relay R^4 , wire 63, thence through windings of relays K^4 and K^6 in parallel, wire 65, and pole changer a^8 back to battery 56. When signal S^8 indicates proceed, therefore, and when relays R^2 , R^3 and R^4 are energized, relay K^4 is picked up, and relay K^6 is energized in such direction that its polar contact is swung to its righthand or normal position. If, however, signal S^8 indicates stop, pole changer a^8 is reversed, and the polarity of the current then supplied to relays K^4 and K^6 is reversed, and relay K^6 is energized in the reverse direction so that its polar contact is swung to the left.

Associated with relay K^6 is a stick relay designated by the reference character V and provided with a pick-up circuit controlled by relay N. This pick-up circuit may be traced from battery 6, through wires 9, 10, 11, 12, 28, 29, 32, and 66, back contact 67 of relay N, wire 68, contact 69 controlled by signal S^6 , wires 70 and 71, winding of relay V and common wire 18 back to battery 6. If, therefore, a westbound train enters section D—E with signal S^6 indicating proceed or caution, the de-energization of relay N following the shunting of relay R^4 , causes relay V to become energized. The opening of relay R^4 also de-energizes relay K^4 , and a stick circuit is then established for relay V which passes from battery 6 over the pick-up circuit just traced as far as wire 32 and thence through wires 33, 72 and 73, back contact 74 of relay K^6 , wire 75, front contact 76 of relay V, wires 71^a and 71, winding of relay V, and common wire 18 back to battery 6. It will therefore be plain that having once been energized by the entrance of a westbound train into section D—E, relay V will subsequently be maintained in its energized condition as long as relay K^6 is de-energized. It should be pointed out in this connection, however, that if signals S^6 is indicating stop when the train enters the section, contact 69 will be open and relay V will not pick up. Furthermore, should an eastbound train approach section D—E, relay K^6 would be de-energized before the train reached point D. It will be explained in detail hereinafter that with relay K^6 de-energized signal S^6 indicates stop, and it follows that the entry of an east-bound train into section D—E cannot pick up relay V.

The switch 3, and signals S^3 , S^5 , S^4 and S^6 governing traffic over the switch, are controlled in part by a manually operable lever designated in general by the reference character L. This lever may be located at a point remote from the switch and signals

which it controls and may be installed, for example, in a central despatcher's office or an interlocking cabin. The lever L is capable of assuming five separate positions indicated by the dotted lines in the drawing and designated "L", "B", "N", "D", and "R". The lever L controls a plurality of contacts each designated by a small circle in which are letters corresponding to the 10 positions of the lever for which such contact is closed. For example, contacts 77, 80, and 81 are closed when the lever is between the "L" and "B" positions, and contacts 78, 79 and 82 are closed when the lever is between 15 the "R" and "D" positions. The operation of lever L is at times controlled by a lock magnet 140 controlling a dog 144 which cooperates with a locking segment 143 having two lugs 143^a and 143^b which may engage 20 with the locking dog 144.

The lever L controls a polarized relay W located adjacent the switch 3. As shown in the drawing, the lever L occupies its normal position and the relay W occupies its normal position. If the operator wishes to reverse the switch 3, he moves lever L toward the "R" position. Since magnet 140 is de-energized, the motion of the lever L is arrested at the "D" position by engagement of the dog 144 with lug 143^b. In this position, however the "LB" contacts of the lever are open and the "RD" contacts are closed. Current then flows from battery 43, through wires 123 and 83, contact 84 of a timing device t, wire 85, contact 79 of lever L, wires 86 and 87, winding of relay W, wires 88, 89 and 90, contact 78 of lever L, wires 91 and 92, contact 93 of timing device t, and wires 94, 95 and 96, back to battery 43. Under these conditions, the current supplied to relay W from battery 43, energizes relay W in the reverse direction so that its polar armatures are swung to the left. The relay W controls a second polar relay T and when relay W is energized in the reverse direction, a circuit is closed from battery 6, through wires 9, 10 and 97, front contact 98 of relay K⁵, wire 99, front contact 100 of relay Y, wires 101 and 102, front contact 103 of relay Q, wire 104, reverse contact 105 of relay W, wire 106, winding of relay T, wire 107, front contact 109 of relay N, wire 110, reverse contact 111 of relay W, wire 112 and common wire 18 back to battery 6. It should be observed that the circuit just traced for relay T includes a front contact of relay Y, so that the circuit can be closed only if the track from A to D is unoccupied. Furthermore, the circuit includes a front contact of relay Q so that the relay T can be moved from normal to reverse only if all of the signals associated with section D-E are at stop. It should also be noted that since relay N is controlled by a track relay R⁴ and since relay K⁵ is controlled by relays N and

R^6 , the circuit for relay T which includes front contacts of relays N and K^5 , can be closed only if sections $D-E$ and $E-F$ are both unoccupied.

The switch 3 is operated by a motor designated in general by the reference character M and comprises an armature 116 and a field 121. The motor is controlled in part by a contact device operated by the switch 3 and comprising a contact 119—119^a which is closed at all times except when the switch occupies its full reverse position and a contact 119—119^b which is closed at all times except when the switch occupies its full normal position. When relay T becomes energized in its reverse direction, current from battery 6 flows through wires 9, 113 and 236, reverse contact 114 of relay T, wire 115, armature 116 of motor M, wire 117, reverse contact 108 of relay T, wire 118, contact 119—119^a operated by switch 3, wire 120, field 121 of motor M, and wires 122, 122^a and 124, back to battery 6, through batteries 7 and 8 in series. When the circuit just traced is closed, therefore, the combined electromotive forces of batteries 6, 7 and 8 are applied to the field and armature of motor M, thereby operating the motor in such direction as to shift switch 3 towards its reverse position. When the switch attains its full reverse position, contact 119—119^a opens, thereby de-energizing motor M. With the switch in its reverse position, however, contact 134—134^b is closed and current from battery 6 then flows through wires 9, 113 and 135, contact 134—134^b, wires 136, 89, and 137, contact 82 of lever L, wires 138 and 139, winding of magnet 140 and wires 141, 141^a and 142, pole changer α^6 controlled by signal S⁶ in its stop position, and common wire 18 back to battery 6. It has already been explained that it is necessary for signal S⁶ to indicate stop before relay T can be operated. The circuit just traced is completed, therefore, as soon as the switch attains its reverse position, thereby energizing magnet 140 and withdrawing the dog 144 from the locking segment 143. The lever L may then be moved to its full reverse position.

If the operator wishes to restore the switch 115 to its normal position, he does so by moving the lever L toward the "L" position. The motion of the lever is arrested at the "B" position by engagement of dog 144 with lug 143^a on locking plate 143, the circuit for magnet 140 having been opened when the "RD" contact 82 of lever L was opened. The "LB" contacts on the lever L are now closed and current from battery 43 flows over wires 123 and 83, contact 84 of timing device t, wires 85 and 125, contact 77 of lever L, wires 90, 89 and 88, winding of relay W, wires 87 and 86, contact 80 of lever L, wire 92, contact 93 of timing device t, and wires 94, 95 and 96, back to battery 43. Relay W 120 125 130

therefore swings its polar armatures to the right or normal positions. An operating circuit is now closed for relay T from battery 6, through wires 9, 10, 11, 12 and 126, 5 front contact 127 of relay R³, wires 128 and 129, front contact 130 of relay Q, wire 131, normal contact 111 of relay W, wire 110, front contact 109 of relay N, wire 107, winding of relay T, wire 106, normal contact 105 10 of relay W, wire 132, and common wire 18 back to battery 6. The circuit just traced includes a front contact of relay Q and a front contact of relay R³ and it follows that relay T can be energized in the normal direction 15 only if all of the signals indicate stop and section C—D is unoccupied. When relay T is energized in the normal direction, current from batteries 6, 7 and 8 in series flows through wires 9, 113, and 236, normal 20 contact 108 of relay T, wire 117, armature 116 of motor M, wire 115, normal contact 114 of relay T, wire 237, contact 119—119^b controlled by switch 3, wire 120, field 121 of motor M, and wires 122, 122^a and 124, back to 25 battery 8. The motor M is therefore operated to move the switch 3 toward its normal position. When the switch attains its full normal position, contact 119—119^b opens and discontinues the supply of energy to 30 the motor M. With the switch in its full normal position, magnet 140 is energized by current which flows from battery 6, through wires 9, 113 and 135, contact 134—134^a operated by switch 3, wires 144 and 86, 35 contact 81 of lever L, wire 139, winding of magnet 140, wires 141, 141^a and 142, pole changer α^6 operated by signal S⁶ in its stop position and common wire 18 back to battery 6. Magnet 140 therefore lifts the dog 40 144 out of engagement with the locking segment 143 and permits the lever L to be moved to its full "L" position.

It has been pointed out that relay T can not be energized in its reverse direction after 45 an eastbound train approaching the switch, has passed point A, nor can the relay be energized in its normal direction after an eastbound train, approaching the switch, has passed point C. It is desirable under some 50 conditions to release this approach locking, so that after a train has approached the switch 3 within the limits which are defined by the approach locking, the operator of the lever L may take action to reverse the switch under proper precautions to insure the safety of trains. In my present invention this is accomplished by a relay X which 55 may be energized to close a branch for the circuit of relay T under predetermined conditions. One pick-up circuit for relay X is controlled by the timing device t located adjacent the lever L. The timing device t may be a clock work time release of the usual and well known form and, comprises a handle which normally occupies the position

shown in the drawing in which contacts 175, 172, 84 and 93 of the device are closed. When the timing device is operated, certain other contacts 151 and 146 are closed and when the device is released a measured interval of time elapses before the device returns to its initial condition. When the timing device t is operated, current from battery 43 is supplied to relay X over a circuit which passes through wires 123, 83 and 145, contact 146 of timing device t, wire 147, front contact 148 of relay Q, wire 149, winding of relay X, common wire 18 to pole changer α^6 and thence through wires 142, 141^a and 150, contact 151 of timing device t, and wires 152, 95 and 96, back to battery 43. If, therefore, relay Q is energized when timing device t is operated, relay X is picked up. Having once been energized, relay X may subsequently be held in its energized condition 80 as long as relay Q remains energized, by current from battery 6, which flows over a circuit through wires 9, 155, 165 and 156, front contact 157 of relay X, wires 158 and 159, front contact 160 of relay Q, wire 161, front contact 148 of relay Q, wire 149, winding of relay X and common wire 18 back to battery 6. Relay X, having once been energized to close its stick circuit, is held in its energized condition until one of the signals 85 associated with section D—E is cleared to de-energize relay Q.

When relay X is energized, if relay W occupies its normal position, a shunt is closed around front contact 127 of relay R³ 90 in the circuit for relay T, so that the circuit for this relay may now be traced from battery 6, through wires 9, 155 and 165, front contact 163 of relay X, wires 164 and 129, front contact 130 of relay Q, wire 131, normal contact 111 of relay W, wire 110, front contact 109 of relay N, wire 107, winding of relay T, wire 106, normal contact 105 of relay W, wire 132, and common wire 18 back to battery 6. If, therefore, relay X is energized to release the approach locking, energization of relay W in the normal direction will energize relay T in the normal direction provided only that all of the signals 100 associated with section C—D indicate stop and the section is unoccupied. In similar manner, it should be observed that when relay X is energized front contact 100 of relay V and front contact 98 of relay K² are shunted out of the reverse operating circuit 105 for relay T so that if relay W is energized in the reverse direction, a circuit is closed for relay T from battery 6, through wires 9 and 155, front contact 166 of relay X, wires 167 and 102, front contact 103 of relay Q, wire 104, reverse contact 105 of relay W, wire 106, winding of relay T, wire 107, front contact 109 of relay N, wire 110, reverse contact 111 of relay W, wire 112 and common 110 wire 18 back to battery 6. It follows, there-

fore, that if relay W is reversed when relay X is closed, relay T is swung to the reverse position to reverse switch 3 provided only that all of the signals associated with section 5 D—E are at stop and the section is unoccupied.

It is sometimes desirable to inform the operator in charge of lever L when a train passes point A, because when a train passes 10 this point, relay Y becomes de-energized and it is then necessary to operate the timing device t to move the switch from normal to reverse. It is also desirable to inform the operator when a train enters section D—E. 15 This information is given to the operator by means of a lamp 184 which is controlled by an indication relay Z. When relay Z is energized, current from battery 43 flows through wires 123, 44 and 238, front contact 20 182 of relay Z, wire 183, lamp 184 and wires 108, 55 and 96 to light the lamp 184. Relay Z is arranged to be energized for a brief interval when an eastbound train passes point A, the operation being as follows:

25 When the train enters section A—B, relay R¹ becomes de-energized, thereby de-energizing relay Y. This relay immediately drops, and breaks the circuit for relay P. As has already been explained, a time interval 30 elapses after the de-energization of relay Y and prior to the opening of front contact 180 of relay P. During this brief time interval, current flows from battery 6, through wires 9, 10, 11, 12, 28 and 177, back contact 35 178 of relay Y, wire 179, front contact 180 of relay P, wires 181, 147 and 171, contact 172 of timing device t, wire 173, winding of relay Z, wire 174, contact 175 of timing device t, wires 176, 150, 141^a and 142, pole 40 changer a⁶ operated by signal S⁶, and common wire 18 back to battery 6. It will be plain from the foregoing that when a train passes point A, relay Z becomes energized. As soon as relay P releases its front contact 45 180, the circuit just traced for relay Z is interrupted, and the relay then becomes de-energized. The lamp 184 is, therefore flashed for a brief interval of time to indicate to the operator of lever L that a train 50 has passed point A.

Another circuit is provided for relay Z which may be traced from battery 6, through wires 9, 10, 11 and 168, back contact 169 of relay R⁴, wires 170 and 159, front contact 55 160 of relay Q, wires 161, 147 and 171, contact 172 of timing device t, wire 173, winding of relay Z, wire 174, contact 175 of timing device t, wires 176, 150, 141^a and 142, pole changer a⁶ controlled by signal S⁶, and 60 common wire 18 back to battery 6. When the train enters section D—E, therefore, relay R⁴ will be de-energized, and if relay Q is energized, current will then be supplied over the circuit just traced to hold relay Z 65 in its energized condition. When lamp 184

is continuously energized, therefore, the operator is informed that a train occupies section D—E.

Signal S² is controlled in part by a relay K² and in part by a manually operable 70 switch r as has already been mentioned. When signal S⁶ indicates caution or proceed, the pole changer a⁶ controlled thereby, occupies the position in which it is illustrated in the drawing. Under these conditions, 75 current from battery 7 flows through common wire 18 to pole changer a⁶, thence through wire 199, front contact 198 of relay R⁶, wire 197, winding of relay K², wires 196 and 142, pole changer a⁶, wires 153 and 195, 80 front contact 194 of relay K⁶, wire 193, contact 192 of circuit controller U operated by switch 3, wire 191, normal contact 190 of relay W, wire 189, front contact 188 of relay W, wire 187, front contact 186 of relay N, 85 and wire 185 back to battery 7. When this circuit is closed, relay K² is energized in the normal direction so that its polar contact is swung to the right. If signal S⁶ is at stop, 90 however, so that pole changer a⁶ is reversed, the circuit for relay K² may be traced from battery 6, through wires 9, 10, 11, 12, 28, 29, 32, 33, 72 and 73, front contact 200 of relay K⁶, wires 214 and 201, pole changer a⁶, wire 199, front contact 198 of relay R⁶, 95 wire 197, winding of relay K², wires 196 and 142, pole changer a⁶, and common wire 18 back to battery 6. When this circuit is closed, relay K² is energized in the reverse 100 direction so that its polar armature is swung to the left.

The signal S² is controlled in accordance with the position of relay K² by virtue of circuits which I will now describe. One circuit for signal S² may be traced from battery 43, through wires 123, 44, 162 and 202, front contact 203 of relay R⁷, wire 204, switch r, wire 205, front contact 206 of relay K², wire 207, operating mechanism of signal S², and wires 208, 54, 55 and 96, back 110 to battery 43. It will be plain therefore that when the switch r is closed, and when relay K² is energized, the circuit just traced for signal S² is closed and under these conditions the signal indicates caution. If switch r is closed when relay K² is energized in the normal direction, current flows from battery 43, through wires 123, 44, 162 and 202, front contact 203 of relay R⁷, wire 204, switch r, wire 205, front contact 206 of relay K², wire 209, normal contact 210 of relay K², wire 211, operating mechanism of signal S² and wires 208, 54, 55 and 96 back to battery 43. When this circuit is closed, signal S² indicates proceed. When relay K² is de-energized or when the switch r is open, both the operating circuits for signal S² are open and the signal indicates stop. In actual practice, the switch r controlling signal S² is usually 120 interlocked with the apparatus which con- 130

trols signals S^7 and S^9 to prevent clearing of signals for conflicting routes at the same time.

As shown in the drawing, the track is unoccupied and signals S^8 and S^1 both indicate stop and lever L occupies its "L" position. Relays W and T are energized in their normal directions and switch 3 occupies its normal position. All of the track relays are energized and relays K^4 , K^6 and K^2 are energized in their normal directions, but relay K^5 is energized in its reverse direction because pole changer a^9 controlled by signal S^9 is reversed. An operating circuit for signal S^5 is now closed from battery 8 , through wire 185 , front contact 186 of relay N , wire 187 , front contact 188 of relay W , wire 189 , normal contact 190 of relay W , wire 191 , contact 192 of circuit controller U , wire 215 , front contact 216 of relay K^5 , wire 217 , operating mechanism of signal S^5 , and wires 122^a and 124 back to battery 8 . The circuit just traced is provided with a branch which passes from front contact 216 of relay K^5 , through wire 218 , normal contact 219 of relay K^5 , wire 220 , operating mechanism of signal S^5 , and wire 124 back to battery 8 . This branch is now open, however, because relay K^5 is energized in the reverse direction and under these conditions signal S^5 indicates caution.

A circuit for signal S^6 may be traced from battery 8 , through wire 185 , front contact 186 of relay N , wire 187 , front contact 188 of relay W , wire 189 , normal contact 190 of relay W , wire 191 , contact 192 of circuit controller U , wire 193 , front contact 194 of relay K^6 , wires 195 and 221 , operating mechanism of signal S^6 , and wires 222 , 122^a and 124 , back to battery 8 . When this circuit is closed, signal S^6 indicates caution. The circuit just traced for signal S^6 is provided with a branch from front contact 194 of relay K^6 , through wire 223 , normal contact 224 of relay K^6 , wire 225 , operating mechanism of signal S^6 to wire 222 . This branch is now closed because relay K^6 is energized in its normal direction and signal S^6 therefore indicates proceed. Signals S^4 and S^3 indicate stop.

If now, the operator wishes to reverse switch 3 , he moves the lever L to the "D" position as has been described hereinbefore. Relay W first becomes de-energized and then becomes energized in the reverse direction. As a result the operating circuits for signals S^6 and S^5 are interrupted and these signals go to stop. With all the signals associated with section D-E now indicating stop, relay Q picks up, whereupon relay T becomes energized in the reverse direction to reverse switch 3 . When the switch 3 has reached its full reverse position, circuit controller U reverses, and signal S^3 moves to the caution position, its operating

circuit being closed from battery 8 , through wire 185 , front contact 186 of relay N , wire 187 , front contact 188 of relay W , wire 189 , reverse contact 190 of relay W , wire 226 , contact 227 of circuit controller U , wires 228 and 229 , operating mechanism of signal S^3 , and wire 124 back to battery 8 . The circuit just traced is provided with a branch which passes from wire 228 , through wire 230 , back contact 231 of relay R^5 , wire 232 , front contact 233 of relay K^4 , wire 234 , operating mechanism of signal S^4 , wires 235 , 222 , 122^a and 124 back to battery 8 . This branch just traced includes a back contact of relay R^5 and the signal S^4 therefore indicates stop until a train enters a section H-J, whereupon relay R^5 drops, to complete the branch just traced, causing signal S^4 to indicate proceed. In similar manner, if the operator restores lever L to its "L" position, the de-energization of relay W interrupts the circuit for signal S^5 , and also for signal S^4 should this signal be cleared, and when relay W next becomes energized in the normal direction, relay T becomes energized in its normal direction to restore switch 3 to its normal direction. When this occurs, the signal S^5 returns to its caution position and signal S^6 returns to proceed position.

With the parts occupying the positions in which they are illustrated in the drawing, I will next assume that a train moving from west to east, passes point A. As a result, relay Y becomes de-energized. If, now, the operator attempts to reverse switch 3 by moving lever L toward its "R" position, relay W will become energized in its reverse direction, and thereby set all of the signals associated with section D-E at stop, but the circuit for relay T is now open at front contact 100 of relay Y and the switch can not be reversed. It should also be pointed out that at the instant the train entered section A-B, relay Z became energized for a brief interval to flash lamp 184 , thus informing the operator that the approach locking has been effective. Under these conditions, if the operator wishes to reverse the switch, he may do so by operating the timing device t . When this occurs, relay X becomes energized and is subsequently held in its energized condition as long as relay Q is closed. It should be pointed out, however, that upon operation of device t , contacts 84 and 93 are opened, and that these contacts do not close again until after the expiration of a time interval following the operation of the device. During this time interval, it is impossible for current to be supplied to relay W so that this relay is de-energized and reversal of the switch 3 is prevented until the contacts 84 and 93 of device t are again closed. Furthermore, while device t is being operated, the relay Z is disconnected from wire 147 , so that the energy which is

supplied to wires 147 and 150 to energize relay X can not actuate relay Z to give a false indication to the operator. After the timing device t has returned to its normal condition, 5 the operator may reverse the switch 3 by proper manipulation of lever L, the operation of the apparatus in response to the consequent reversal of relay W being readily understood from the foregoing explanation.

10 I will now assume that the switch occupies its reverse position and that the train occupies section A—B or B—C. Relay Y is de-energized but no contact of relay Y is involved in that circuit for relay T which energizes the relay in its normal direction. It follows that the operator may move switch 15 3 to its normal position by operating lever L to its "L" position at any time prior to the entry of the train into section C—D. If, 20 however, the train is actually in section C—D, relay R³ is de-energized and contact 127 is therefore open. If the operator now moves lever L toward its "L" position in an attempt to restore the switch to its normal 25 position, the relay W will become energized in its normal direction but since the circuit for relay T is now open at front contact 127 of relay R³, the operation of the switch 3 is prevented. Even with the train occupying 30 section C—D, however, the operator may reverse the switch if he releases the approach locking by operation of the timing device t . If this occurs, relay X picks up and a branch 35 is closed for the circuit of relay T, through front contact 163 of relay X around front contact 127 of relay R³. When the timing device t returns to its original condition, 40 therefore, relay W again picks up and relay T swings to its normal position to restore the switch to its normal position. It should 45 be pointed out that if a train occupying section D—E, relay N is de-energized so that front contacts 109 and 186 are open. Under these conditions, the circuit for relay T is open so that this relay becomes de-energized, opening the operating circuit for motor M. It follows that it is impossible to 50 actuate the switch 3 when any portion of a train occupies the section D—E.

55 The operator may place at stop all the signals associated with section D—E at any time by simply moving lever L to its N position. This opens all contacts of the lever and de-energizes relay W, thereby interrupting at front contact 186, all circuits for signals S³, S⁵, S⁴ and S⁶.

60 For purposes of simplicity, I have illustrated apparatus for accomplishing approach locking of the switch 3 only in response to trains approaching the switch from the west but it should be distinctly understood that I do not wish to be limited to apparatus of this scope but that similar apparatus could be provided for accomplishing approach locking for westbound traffic.

Although I have herein shown and described only one form of railway traffic controlling apparatus embodying my invention, it is understood that various changes and modifications may be made therein within 70 the scope of the appended claims without departing from the spirit and scope of my invention.

Having thus described my invention, what I claim is:

1. In combination, a railway switch, a manually controlled lever, a first polarized relay controlled by said lever, a second polarized relay, means responsive to traffic conditions for at times energizing said second polarized relay in one direction or the other according as the first polarized relay is energized in one direction or the other, and a motor controlled by said second polarized relay for moving said switch to its 80 normal or reverse position according as said second polarized relay is energized in one direction or the other.

2. In combination, a railway switch, a manually controlled lever, a first polarized relay controlled by said lever, a normally energized approach relay arranged to be de-energized when a train moving in one direction approaches said switch, a second polarized relay controlled by said first polarized 90 relay and by said approach relay, and a motor controlled by said second polarized relay for operating said switch.

3. In combination, a railway switch, a manually controlled lever, a first polarized 100 relay controlled by said lever, a first contact arranged to be opened when a train approaching said switch passes a definite point, a second contact arranged to be opened when a train approaching said switch passes a different point, a second polarized relay, means including said first contact and a normal contact of said first polarized relay for energizing said second relay in the normal direction, means including said second contact 105 and a reverse contact of said first relay for energizing said second relay in the reverse direction, and a motor for moving said switch to its normal or reverse position according as said second relay is energized in 110 the normal or reverse direction.

4. In combination, a railway switch, a manually controlled lever, a first polarized relay controlled by said lever, a normally energized approach relay arranged to be de-energized when a train moving in one direction approaches said switch, a second polarized relay controlled by said first polarized 120 relay and by said approach relay, a manually operable timing device, means controlled by said timing device for removing said approach relay from the control of said second polarized relay, and a motor controlled by said second polarized relay for operating said switch.

5. In combination, a railway switch, a manually controlled lever, a first polarized relay controlled by said lever, a stick relay, a first contact arranged to be opened when 45
5 a train approaching said switch passes a definite point, a second contact arranged to be opened when a train approaching said switch passes a different point, a second polarized relay, means including said first 50
10 contact and a normal contact of said first polarized relay for energizing said second relay in the normal direction, a branch around said first contact including a front contact of said stick relay, means including 55
15 said second contact and a reverse contact of said first relay for energizing said second relay in the reverse direction, a branch around said second contact including a front contact of said stick relay, a manually oper- 60
20 able timing device, a pick-up circuit for said stick relay controlled by said timing device, a stick circuit for said stick relay controlled by traffic conditions adjacent the switch, and a motor for moving said switch to its 65
25 normal or reverse position according as said second relay is energized in the normal or the reverse direction.

6. In combination, a railway switch, a manually operable timing device normally occupying an initial position and requiring after actuation a time interval to return to its normal position, a manually operable lever, a first polarized relay controlled by said lever when said timing device occupies 70
30 its initial position, a normally energized relay arranged to be de-energized when a train is approaching said switch, a second polarized relay controlled by said normally energized relay and by said first polarized relay, 75
35 means set into operation when said timing device is actuated and continuing after said 40

timing device returns to its initial position to remove said normally energized relay from the control of said second polarized relay, and a motor controlled by said second polarized relay for operating said switch. 45

7. In combination with a railway switch, a manually operable lever, a first polarized relay controlled by said lever, a second polarized relay controlled by said first polarized relay and by traffic conditions adjacent the switch, a motor controlled by said second polarized relay for actuating said switch, a signal relay controlled by traffic conditions adjacent the switch, and a signal controlled by said signal relay and by said first polarized relay for governing traffic over said switch. 50

8. In combination with a railway switch, a manually operable lever, a first polarized relay controlled by said lever, a normally closed contact arranged to be opened when a train approaching said switch, passes a definite point, a second polarized relay controlled by said contact and by said first polarized relay, a motor controlled by said second polarized relay for actuating said switch, a signal relay, a circuit for said signal relay controlled by traffic conditions adjacent the switch, a signal controlled in part by said signal relay for governing traffic over said switch, an indication relay adjacent said lever, means including a portion of the circuit for said signal relay for energizing said indication relay when a train passes 75
60 said point, a lamp controlled by said indication relay, and manually operable means for at times removing said contact from the control of said second polarized relay. 65

In testimony whereof I affix my signature.

CARL F. STOLTZ.
